UNITED STATES PATENT OFFICE.

WILLIAM ALFRED SMITH, OF BIRMINGHAM, ALABAMA.

TRACK-CROSSING STRUCTURE.

1,120,754.

Specification of Letters Patent. Patented Dec. 15, 1914.

Application filed April 10, 1914. Serial No. 831,006.

To all whom it may concern:

Be it known that I, WILLIAM ALFRED SMITH, a citizen of the United States of America, residing at Birmingham, in the county of Jefferson and State of Alabama, have invented certain new and useful Improvements in Track-Crossing Structures, of which the following is a specification.

My invention relates to improvements in 10 a railway crossing structure having for its object to avoid the jars and jolting of the wheels in passing over crossings and hence to eliminate the noise and excessive wear resulting therefrom both on the wheels and on 15 the supports for the crossing structure.

My invention comprises a rotatable track section at each track intersection of the structure which section is movable into alignment with the track rails on which the 20 wheels of the crossing train or car are traveling.

One important feature of my invention consists in the provision of a safety construction which will prevent serious injury 25 either to wheels or to the movable track section in the event that the latter is not adjusted for any reason whatsoever into alignment with the direction of movement of the train or car.

30 My invention further comprises the details of construction and arrangement of parts which are hereinafter more particularly described and claimed in their preferred embodiment only, reference being 35 had to the accompanying drawings which form a part of this specification, and in which:

Figure 1 is a plan view of a crossing structure equipped with my improved invention. Fig. 2 is a sectional view taken 40 on the line A—A of Fig. 1. Fig. 3 is a cross sectional view taken on the line B—B of Fig. 1, and Fig. 4 is a perspective view of an intersection.

45 Similar reference numerals refer to similar parts throughout the drawings.

In the construction illustrated, a right angled crossing structure is shown comprising track sections 1 and 2, the tracks 2 leading 50 in one direction and at right angles to tracks 1. The tracks shown are of the grooved type customarily in use for street car service in paved streets, but it will be understood that any standard form of rail may be 55 used. Preferably the four meeting ends of the rails 1 and 2 at each intersection are

suitably fastened or cast jointed to a substantially circular casting 3 forming a seat which is provided with a circular recess in its upper face which receives a rotatable element 4 adapted to form a continuation of the tracks 1 or 2, according to its position. This element 4 is preferably constructed as a circular plate which has at the center of its bottom a cylindrical stud 5 which passes 60 through a circular opening in the bottom of the recess in the seat 3 and its lower end which projects below the seat is reduced and provided with a collar or washer 7 which is held fast thereon by a pin 8. The lower end 65 9 of the stud 5 is squared for connection with the operating mechanism hereinafter described.

The element 4 preferably rotates on a series of anti-friction balls 10 which travel in 75 a raceway formed partly in the bottom face of the element 4 and in the upper face of the recess in seat 3.

Around the marginal edge of the recess in which the member 4 turns, I provide a 80 groove 11 from which one or more passages 12 lead downwardly through the casting 3 to drain the water from the seat.

The top face of the circular plate 4 is provided with a diametrical groove 13 extending 85 from edge to edge thereof with the vertical axis of the plate passing through the center of the groove. The top face of the plate 4 stands level with the tread surfaces of the rails 1 and 2 except that at diametrically opposite points, each removed 90° from the ends of the groove 13, I provide inclined treads 14 which lead from the tread level down to the level of the groove 15 in the rails 1 or 2, and on each side of each incline treadway 14 I provide a pair of humped treads 16 and 16' which rise from the peripheral edge of the plate at the same angle as the treads 14 to their centers which stand above the tread level of the rails 1 95 and 2 and of the rest of the top surface of the plate 4. From their raised centers these treads slope down to the level of the top surface of the plate 4 into which they merge at points spaced from the sides of the groove 105 13. The main tread surface of the plate 4 is indicated at 17 and as the element is swung in the direction of the arrow, Fig. 4, it will be evident that this tread surface will swing from alignment with the treads of 110 rails 2 into alignment with the treads of rails 1, and in doing so the incline treads

14 are brought into alinement with the groove of rails 2 and the raised treads 16 stand in alinement with the treads of the rails 2. When the member is in the position shown in Fig. 4, the treads 16' are in alinement with the treads of the rails 1. It will thus be seen that should wheels pass along the tracks 1 when the plates stand in the position in Fig. 4, the wheel flanges will ride up the inclines 14 while their treads will ride up the humped treads 16' which will act to cause the wheels to ride over the movable plate without being destroyed and damaging the crossing structure itself.

15. The ends 9 of the several studs 5 have fast thereon levers 17^a which are connected in pairs by crank arms 18 to disk cranks 19, one of which is disposed adjacent to each track 2 and which are both made fast on a cross rod 20 that turns in suitable bearings 21 made fast to the under side of the rails 2. A crank 22 on the rod 20 is operated by a lever 23 leading to any suitable style of throw mechanism. As this lever 23 is moved from full line to dotted line position, see Fig. 2, the several elements 4 are shifted simultaneously to bring their respective grooves 13 and tread surfaces 17 into alinement with the grooves and treads of the tracks 2 or 1 as the case may be.

The manner of pivoting the rotating plate to one side of its main tread surface adapts the latter to move into alinement with either track.

35. Having thus described my invention, what I claim as new and desire to secure by Letters Patent, is:—

1. A railroad crossing structure including a base plate at each track intersection, crossing rails having their meeting ends made fast to each base plate, a turn table rotatably supported on said plate, said turn table comprising a diametrical tread surface and flange groove and having humped treads disposed in diametrical alinement on opposite sides of said groove, said humped treads being adapted to aline with the track rails with which the turn table's tread surface is not in alinement.

50. 2. In a track structure, a turn table comprising a circular plate having a continuous flange groove across its top face and a tread surface on one side of said groove, and having on each side of said tread surface humped treads raised above the said tread surface, there being short flange grooves beside said humped treads, and means to support and operate said turn table, substantially as described.

60. 3. A railway crossing structure comprising a base plate, the meeting ends of rails

which are made fast to said plate and have their treads level with the top surface of said plate, a rotatable turn table mounted in said plate and having a diametrical flange groove in its top face, which face stands level with the rail treads, an inclined flange tread leading downwardly toward the periphery of the plate on each side of said groove, and humped treads disposed on each side of each downwardly inclined tread, said humped treads being inclined toward their centers which are raised above the tread surface of the plate and being arranged in oppositely disposed pairs across the turn table, the corresponding pairs of said humped treads being adapted to aline with one or the other of the track rails which at the time are disposed at an angle to said flange groove, substantially as described.

4. In a crossing structure, the combination with the meeting ends of rails, of a casting to which said ends are fastened, said casting having a circular seat, a turn table which fits snugly in said seat and has a transverse tread surface level with the marginal edge of the casting and with the treads of the track rails, antifriction bearings for said turn table, said table having a transverse flange groove and having a bottom shank which projects below said casting, and operating mechanism connected to the lower end of said shank for rotating the table to form a continuation of either track rail, substantially as described.

5. In a crossing structure, the combination with the meeting ends of rails, of a seat to which said rail ends are cast jointed, said seat having its marginal top edge level with the treads of the rails and having a central circular recess, a circular plate seated and rotatable in said recess and having a tread surface level with the tread surface of the rails, a diametrical flange groove which extends across the top surface of the plate, and oppositely disposed humped treads on each side of said groove, which treads rise gradually above and merge again into the surface level of the plate, a downwardly inclined flange groove opposite the inner descending ends of said humped treads, said treads being adapted to aline with the meeting rails which stand at an angle to said flange groove, substantially as described.

In testimony whereof I affix my signature in presence of two witnesses.

WILLIAM ALFRED SMITH.
